CLAIM

The ornamental design for a skin touch activated device as shown and described.

DESCRIPTION

FIG. 1 is a top perspective view of the skin touch activated device showing my new design;

FIG. 2 is a bottom perspective view of the skin touch
activated device in FIG. 1;

FIG. 3 is a front view of the skin touch activated device in FIGS. 1 and 2;

FIG. 4 is a rear view of the skin touch activated device in
FIG. 3;

FIG. 5 is a right side view of skin touch activated device in
FIG. 3;

FIG. 6 is a left side view of skin touch activated device in
FIG. 3;

FIG. 7 is a top view of skin touch activated device in FIG.
3;

FIG. 8 is a bottom view of skin touch activated device in FIG. 3; and,

FIG. 9 is a perspective view of the skin touch activated device in use showing my new design.

The broken lines in FIGS. 1-7 and 9 represent portions of the skin touch activated device and form no part of the claimed design. The additional broken lines in FIG. 9 represent environmental subject matter only and form no part of the claimed design.

1 Claim, 9 Drawing Sheets
